CONTAINER WITH FOLDED TOP SEAM

Stellan Birkland, San Francisco, Calif., assignor
to American Can Company, New York, N. Y., a
corporation of New Jersey

Application July 31, 1947, Serial No. 765,054

2 Claims. (Cl. 220—54)

1

This invention relates to sheet metal cans or containers and has particular reference to a container having a novel and material-saving end seam construction which permanently secures and hermetically seals a top closure member to the container and which permits the removal of the closure member so that it may be used as a reclosure.

An object of the invention is the provision of an inexpensive key opening can provided with a reclosing feature which may be manufactured at a saving in materials to make it economically attractive for products not now packed in such cans.

Another object is the provision of such a container of a narrow type of tearing strip formed in the body wall of the can in a portion of the end seam joint which may be removed easily to effect a substantially full opening in the top of the can, which after initially being opened, is reclosable without a reduction in the head space of the can.

Another object is the provision in such a can of an end seam joint formed by overlapped flanges of the can body and the can end member and having the terminal end of the body flange permanently secured in a V-shaped or triangular shaped annular channel formed in the end member by a metallic or non-metallic bonding material such as solder, thermoplastic cement and the like.

Numerous other objects and advantages of the invention will be apparent as it is better understood from the following description, which, taken in connection with the accompanying drawings, discloses a preferred embodiment thereof.

Referring to the drawing:

Figure 1 is a perspective view of a can or container embodying the present invention.

Figure 2 is an enlarged fragmentary vertical section of the container top before tearing strip is removed, taken substantially along a plane indicated by the line 2—2 in Fig. 1; and

Fig. 3 is a view similar to Fig. 2 after the can has been opened and showing its cover in position as a reclosure.

As an exemplary embodiment of the present invention the drawing illustrates a sheet metal can or container comprising a tubular body 11 provided with a side seam 12 and having a bottom 13 permanently secured to the body in any suitable manner as by an end seam 14 and a special reclosure top or end member 15 secured to the body in a novel end seam 16.

2

The reclosure top 15 is formed with a substantially flat raised central panel 17 having a surrounding obliquely disposed wall section 18 merging into an annular depending inner wall 19. The wall 19 adjacent its lower end is bent or folded back against itself to form a hemmed edge 21 which curves upwardly and merges into an upright outer cover flange 22. An upper portion of the flange 22 and the obliquely disposed wall section 18 define a triangularly or V-shaped annular channel or groove 23 therebetween.

When the reclosure top 15 is in sealing position on the can, it fits snugly in the top of the can, just below the upper terminal edge of the can, with its hemmed edge 21 seated on an inwardly extending supporting bead 24 formed in the can body 11 and with its outer flange 22 in engagement with an outer wall 25 of the body 11. The body wall 25 extends up along the outer flange 22 of the reclosure top 15 in parallelism therewith and at its upper end flares outwardly and thence curves inwardly over the top terminal edge of the reclosure outer flange 22 and merges into a depending inner flange 26.

The inner flange 26 of the body 11 extends down into the channel 23 and is secured to the flange 22 and the obliquely bent wall section 18 of the reclosure member 15 by a suitable bonding material 27 which is deposited into the channel 23 in any suitable manner. Such a bonding material may be metallic such as solder or non-metallic such as plastic cement or the like. This overlapping and interfolding of the outer wall 25 and the inner flange 26 of the body 11 with the inner cover wall 19 and the outer cover flange 22 of the reclosure top results in the novel end seam 16 hereinbefore mentioned and provides a permanent, hermetic and economical seam which efficiently seals a container.

Provision is made for readily opening the container by removal of the top 15 in a manner which permits of the use of the removed top as a reclosure member. For this purpose the body outer wall 25 is provided with a narrow removable tearing strip 28. This tearing strip is defined by a pair of spaced and parallel score lines or weakened areas 29 which are formed in the outer wall 25 of the body and which encircle the body and terminate in the body side seam 12. One end of the tearing strip is formed with a tongue 31 which extends beyond the side seam and is engageable by a key 32 or other suitable tool, for removing the tearing strip in the usual manner.

When the tearing strip 28 is removed from the

body outer wall 25 (Fig. 3), the upper portion of this wall 25 together with the body inner flange 26 and the reclosure top 15 still permanently secured thereto, may be readily lifted out of the upper end of the body 11 leaving a full open mouth in the body for easy removal of the contents of the can.

To facilitate removal and replacement of the reclosure top 15, the upper portions of the outer wall 25 and inner flange 26 of the body are flared outwardly along a gradual curved line of bend which provides a convenient hand grip and which also reinforces the top end seam. A bead 35 (Figs. 2 and 3) is formed in the inner flange 26 of the body adjacent the upper edge of the outer flange 22 of the reclosure top 15 for locking the reclosure top in position against the bead 24 in the body 11. In reclosing the container closure member 15 is replaced into its former position on the body bead 24 (Fig. 3) without reducing the head space of the container.

It is evident upon perusal of the drawing that the present container is produced without requiring an extra part such as a collar or additional wall folds in making a permanent end seam. In fact, the seam is formed with one less fold or flange on the outer periphery of the top end member 15. This effects a substantial saving in the amount of metal required for producing such an end and thus reduces the cost of tearing strip containers so that they may be used for a greater variety of products.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A hermetically sealed sheet metal reclosure container comprising a tubular body having a wall terminating at its outer end in a depending flange spaced inwardly from the body wall, said body having an inwardly extending peripheral bead disposed beneath said flange, an end member seated on said body bead on the interior of the container and secured to said body wall in an end seam, said end member having a raised central panel merging into an annular outwardly and downwardly inclined wall portion in turn merging into an annular depending inner wall terminating in an integral upstanding outer contacting flange disposed between and snugly engaging against the inner surface of said body wall and the outer surface of said depending body wall flange, the space between said downwardly inclined wall portion and said upstanding flange of said end member defining an annular groove for receiving the inner end of said depending body wall flange, a sealing material disposed in said groove for embedding therein said depend-

ing flange end of said body wall to provide a hermetic seal between said body and end member, and a tearing strip set off by spaced score lines in said body wall adjacent said upstanding end member flange, removal of said strip effecting severance of said end member from the body to open the container, said end member being thereafter again supported by said inner peripheral body bead as a reclosure cover without reducing the head space of the container.

2. A hermetically sealed sheet metal reclosure container comprising a tubular body having an outwardly flared wall at an end thereof to provide a hand grip, said wall terminating in a depending flange spaced inwardly from the body wall, said body having an inwardly extending peripheral bead disposed beneath said flange, an end closure member seated on said body bead on the interior of the container and secured to said body wall in an end seam, said end member having a raised central panel merging into an annular outwardly and downwardly inclined wall portion in turn merging into an annular depending inner wall terminating in an integral upstanding outer contacting flange disposed between and snugly engaging against the inner surface of said body wall and the outer surface of said depending body wall flange, the space between said downwardly inclined wall portion and said upstanding flange of said end member defining an annular groove for receiving the inner end of said depending body wall flange, a sealing material disposed in said groove for embedding therein said depending flange end of said body wall to provide a hermetic seal between said body and end closure member, said depending body wall flange having an annular bead therein adjacent the terminal end of said upstanding outer end member flange for locking said end member in seated position on said inwardly extending body bead, and a tearing strip set off by spaced score lines in said body wall adjacent said upstanding end member flange, removal of said strip effecting severance of said end member from the body to open the container, said end member being thereafter again supported by said inner peripheral body bead as a reclosure cover without reducing the head space of the container.
